Meyers, Cavanaugh & Hyde

UNITED STATES PATENT OFFICE.

HENRY FRATERNALI, OF DOBBS FERRY, NEW YORK.

CUSHION-HEEL FOR SHOES.

1,391,885.

Specification of Letters Patent. Patented Sept. 27, 1921.

Application filed January 13, 1921. Serial No. 436,918.

To all whom it may concern:

Be it known that I, HENRY FRATERNALI, a citizen of Italy, and resident of Dobbs Ferry, in the county of Westchester and State of New York, have invented certain new and useful Improvements in Cushion-Heels for Shoes, of which the following is a specification.

My invention relates to an improvement 10 in a heel for a shoe, and more particularly to a heel for providing a continuous rolling and yielding engagement of the shoe from any point of heel impact to the point of sole impact of the shoe with an engaged 15 surface such as the ground.

Prior to my invention various forms of 20 heels have been constructed and used, which were intended to provide a cushioning effect for reducing the impact of the heel with the ground. These devices have various provisions for securing a yielding engagement 25 when the heel of the shoe comes in contact with the ground, but such devices do not embody means which will reduce in any substantial manner the second impact incident 30 to the engagement of the flat portion of the heel and the sole portion of the shoe with the ground.

In the act of walking, the heel portion of 35 the shoe first comes in contact with the ground with the plane of the sole at an angle to the plane of the engaged surface, this contact resulting in the first impact of the shoe with the ground. The shoe then rotates about the engaged portion of the heel, which is usually the edge of the heel, until the plane of the sole is substantially in the 40 plane of the engaged surface. In this last position the flat of the heel and with it the sole now contact the ground, this contact resulting in a second, which in most cases is a substantial impact.

A primary object of my present invention is to provide means for materially reducing 45 not only the initial heel impact of the shoe, but also this secondary or combined heel and sole impact.

A further object is to provide a simple 50 heel construction so proportioned as to accomplish these functions.

A still further object is to provide a heel 55 of the type referred to and a support therefor which will effectively retain the heel on the shoe.

To the accomplishment of the foregoing and such other objects as may hereinafter

appear, my invention consists in the elements and their relation one to the other, as hereinafter particularly described and then sought to be defined in the claims, reference being had to the accompanying drawings showing preferred embodiments of my invention and in which:

Figure 1 is a view partly in cross section showing the construction of one form of 60 my improved heel and its attachment to the heel portion of the shoe,

Fig. 2 is a rear end elevational view of the same showing in full lines the condition of the heel when a full downward 70 weight is exerted upon it,

Fig. 3 is a bottom plan view of the same,

Fig. 4 is a view of the same showing the 75 position of the heel as it first reaches the ground in the making of a normal step, with the sole at an angle to the plane of the engaged surface, this view showing both normal and depressed positions,

Figs. 5, 6 and 7 are cross sectional views 80 of modified forms of my improved heel.

Referring to the forms shown in Figs. 1 to 4, the heel comprises a body 10, made of any desirable material, preferably of rubber, and having an outer contour so as to provide a continuous rolling engagement 85 from a first point of heel impact to a last point of heel impact, such contour being preferably, as shown in the drawings, of hemispherical shape, the body of the heel being preferably of a dimension so that the 90 diameter of the sphere substantially equals the full heel portion of the shoe. This body may be made of solid material but the preferred form includes a hemispherical shell, as shown in Fig. 1, having an outer surface 95 11 and an inner surface 12. This body is supported on the heel portion of the shoe, 100 preferably by means of a plate 13 having an annular flange portion 14, this forming a socket which receives the base portion of 105 the heel. The heel is provided with an annular recess 15, in which is seated an annular ring 16, this ring being connected to the flange 13 in any desired manner, as for example, by being brazed thereto. To provide 110 further supporting means for the interior of the heel there is provided, as shown in the drawings, a disk 17 seated in an internal annular recess formed in the surface 12 of the heel, said disk being connected to plate 18 in any desired manner, as by bolt 19. These parts form a suitable supporting

means for both the outside and the inside of the heel. In order to secure a further resilient effect, the space defined by the interior surface of the shell is provided with 5 a compression spring 18', one end of which is seated against the disk 17, the other end of which is seated on a block 19 formed with the heel body 10.

Means is provided for attaching this heel

- 10 and its support to the heel portion of the shoe, such means preferably consisting of lugs 20, which may be formed integrally with plate 13, such lugs being attached to the periphery of the heel portion of the shoe
- 15 in any desirable way, as by screws or nails shown in the drawings.

As a further means for attaching the combined heel and its support to the heel portion of the shoe, there is provided a clip 21 20 connected to the shoe in the manner shown in Fig. 1 and connected to the heel body as by brazing the clip to the ring 16; and also a plate 22 similarly connected to the heel body 10 and connected to the heel portion of the 25 shoe as by bolt 23, said plate being preferably formed with a curved portion 23' engaging the upper of the shoe. It will be seen from this form of the device that when the heel first contacts the ground, as shown in 30 Fig. 4, with the plane of the sole at an angle to the plane of the ground, the spring will be depressed and the heel slightly deformed as shown in dotted lines in Fig. 4, providing an initial impact which is a resilient impact; and further providing a relatively broad surface engagement of the heel with the ground. As the foot rotates and the plane of the sole approaches the plane of the ground, the shoe will rotate on the heel, 40 bringing a different portion of the heel in engagement with the ground until there is reached an osculating plane of the heel which is parallel to the plane of the plate 13. During the rotation of the shoe a continuous 45 rolling engagement of the shoe is provided, yielding at all times a relatively large surface contact of the shoe with the ground and reducing any secondary impact normally resulting when the ordinary flat heel 50 portion comes in contact with the ground; and also considerably eliminating the impact of the sole portion of the shoe with the ground, due to the continuous and rolling engagement provided by the contour of the 55 body portion 10. By providing a shell like heel portion having a resilient element such as a compression spring mounted in the core thereof, there is provided not only an effective resilient or cushion heel construction 60 presenting a relatively broad surface engagement of the heel with the ground and providing, moreover, a larger wearing surface as pointed out above, but there is also provided a construction which permits the 65 use of the desired convex heel configuration

in a shoe where a high arch is to be avoided. This is shown, for example, in Fig. 2 of the drawings, in which in use under the weight of the wearer the hemispherical heel will be depressed or deflated to the normal proportions as regards thickness or height of the flat heels generally in use. It will be, furthermore, apparent that these functions may in a measure be accomplished by the hemispherical shell-like body having a hollow 70 core *per se*, but it is preferred to provide a resilient element in core co-operating with the inner wall of the shell-like heel, the resilient element preventing too great a deflation of the heel when subjected to the 75 weight of the wearer, this construction furthermore effecting a quick return of the heel to convex or hemispherical configuration immediately upon the wearer lifting the shoe 80 from the ground.

In the form shown in Fig. 5 different means is provided for supporting the heel and for connecting the heel body to the shoe, such means comprising a plate 24 having a flange portion 25 connected to the outer rim 90 of the heel in any desirable manner, as by screws or nails 26, the plate being connected to the shoe by attachment to another plate 27, the plates being preferably riveted, as shown in the drawings. To supply for 95 the support of the inner portion of the heel and for the yieldable means in the core of the shell, there is provided a male member 28 connected to the plate 27, this male member receiving the yieldable female member 100 29, connected to the interior surface of the shell 10, as by screws or nails 30, a spring 31 being interposed between the male member 28 and a block of wood 32 to provide the 105 resiliency, as pointed out above.

In the form shown in Fig. 6, different means is provided for supporting the heel body and for connecting the support to the shoe, such means consisting of a plate 32' having annular portions forming a socket 110 for the body 10, said plate being connected to another plate 33 by a bayonet jointing means, as shown in the drawings. This form of the device provides ready means of attachment for plate 32 supporting the heel 115 body which may be simply inserted in socket 33 and rotated in said socket for interlocking engagement. The compression spring 34 is also provided in this form of the device, the same being seated between the 120 plate 32 and a block of wood 35.

In the form shown in Fig. 7, the supporting means consists of a socket 36 receiving the body 10 and a threaded block 37 connected to said socket, as by screws shown 125 in the drawings, said threaded block being received by a correspondingly threaded portion of the interior surface of the shell 10. In this form, as in the other forms of the device, a compression spring 38 is provided, 130

which is seated against the block 37 and another block 39.

The operation of my improved heel is apparent from the above description thereof.

- 5 It will be seen that I have provided a heel construction which accomplishes the functions intended in providing a continuous and yielding engagement of the heel with the ground in the act of walking, which will 10 give an initial yielding impact of the heel on the ground and which will eliminate any further heel impact and considerably reduce the sole impact of the shoe with the ground, this construction also providing a relatively 15 large surface engagement of the heel with the ground at all times of heel contact, this also yielding a relatively large wearing surface instead of a small wearing surface, as in the usual heel, resulting in a longer life 20 of the heel. In some forms of shoes where it is not feasible to have too large a heel, a solid block of resilient matter may be used, which may be in the form of a quadrant of 25 a sphere instead of a hemisphere, the quadrant being so proportioned that a rolling contact will be provided from a point of impact of the heel with the sole of the shoe at a maximum angle of about forty-five degrees to the plane of the ground to the point 30 where the plane of the sole is substantially in the plane of the ground.

While I have shown my device in the preferred forms, it will be obvious that various changes and modifications may be made in 35 the structure disclosed without departing from the spirit of the invention, defined in the followings claims.

I claim:

1. A resilient heel adapted for attachment 40 or connection to the heel portion of a shoe, said resilient heel including a substantially hemispherical body, the heel body comprising an elastic shell structure having a hollow core, the core defining a cavity when 45 the resilient heel is attached or connected to the heel portion of the shoe.

2. A resilient heel adapted for attachment or connection to the heel portion of a shoe, said resilient heel comprising a shell-like body having inner and outer surfaces, the outer surface being adapted for continuous 50 rolling contact from the point of heel impact to the point of sole impact of the shoe, the shell-like body having a hollow core with the core defining a cavity when 55 the resilient heel is attached to the heel portion of the shoe and a supporting means for the heel providing means of attachment with the shell at the said inner and outer surfaces. 60

3. A resilient heel adapted for attachment or connection to the heel portion of a shoe, said resilient heel comprising a substantially hemispherical elastic shell-like body, the outer surface of which is adapted 65 for continuous rolling contact with a plane of engagement; said shell-like body having a hollow core with the core defining a cavity when the resilient heel is attached to the heel portion of the shoe and resilient means 70 mounted in the core of said shell and cooperating with the inner surface thereof.

4. A resilient heel adapted for attachment or connection to the heel portion of a shoe, said resilient heel comprising an elastic 75 shell-like body having inner and outer surfaces, the outer surface being adapted for continuous rolling contact with a plane of engagement, said shell-like body having a hollow core, with the core defining a cavity 80 when the resilient heel is attached to the heel portion of the shoe, a supporting means therefor providing means of attachment with said shell at the said inner and outer surfaces, and resilient means mounted in the 85 core of said shell engaging said support and the inner surface of the shell.

Signed at New York, in the county of and State of New York, this 10th day of November, A. D. 1920.

REV. HENRY FRATERNALI.
